DESCRIPTION

A portion of the disclosure of this patent document contains
material to which a claim for copyright is made. The copy-
right owner has no objection to the facsimile reproduction by
anyone of the patent document or the patent disclosure, as it
appears in the Patent and Trademark Office patent file or
records, but reserves all other copyright rights whatsoever.
The single FIGURE is a front view of a computer display
screen with a graphical user interface showing our new
design.

The outermost broken lines in the figure show a computer
display screen, and form no part of the claimed design. The
other broken lines in the figure show portions of graphical
user interface that forms no part of the claimed design.

The claimed design is a computer-generated image for a
computer display which conveys the impression of a translu-
cent/transparent surface.
